UNITED STATES PATENT OFFICE.

CHARLES E. REDDIG, OF RICHMOND HILL, NEW YORK, ASSIGNOR TO WESTERN ELECTRIC COMPANY, INCORPORATED, OF NEW YORK, N. Y., A CORPORATION OF NEW YORK.

CLOTHES WRINGER.

Application filed September 14, 1920. Serial No. 410,114.

To all whom it may concern:

Be it known that I, CHARLES E. REDDIG, a citizen of the United States, residing at Richmond Hill, in the county of Queens, 5 State of New York, have invented certain new and useful Improvements in Clothes Wringers, of which the following is a full, clear, concise, and exact description.

This invention relates to clothes wringers. 10 The general object of the invention is to provide a wringer having convenient and efficient means for releasing and restoring the tension which holds the rollers in engagement. Other objects are the provision 15 of new and improved feed boards and movable drain board. The invention is particularly applicable to wringers which are power driven, although it is also applicable to and useful in connection with hand-driven 20 wringers.

It is desirable in all clothes wringers that means be provided for releasing the pressure of one roller upon the other when the machine is not in use. Unless such means is 25 easily operated, operators are likely to neglect using it, with consequent damage to the rollers while the machine stands idle.

It is also highly important, in connection with power-driven wringers, to provide 30 easily operated means whereby the tension on the movable roller is instantly released and the latter allowed to move freely away from the other roller, in case the fingers of the operator become pinched between the 35 rollers. Experience has proven, however, that if such releasing means is inconvenient to operate or if it is purely a safety device which is not used during the normal operation of the machine, then the operator may 40 fail to use it in an emergency but instead will attempt to release her fingers by operating the handle which controls the starting and stopping of the rollers.

In other words, the more readily operable 45 the tension releasing and restoring arrangement is, the more apt the operator is to use it during the normal operation of the wringer when the latter is left idle or is stalled by an attempt to put too large an 50 amount of clothing through it at one time. And if the operator thus becomes accustomed to using the releasing arrangement frequently during the normal operation of the

machine, then it is probable that if the fingers of one hand become pinched between 55 the rollers she will almost instinctively actuate the releasing device with her other hand. The present invention takes these facts into account, and provides a clothes wringer in which the pressure of the movable roller upon the fixed roller may be 60 easily and instantly released and restored during the normal operation of the machine as well as in an emergency due to the pinching of the operator's fingers. 65

The invention will be understood from the following description taken in connection with the accompanying drawings in which one embodiment is illustrated. In the drawings, Fig. 1 is a front elevation of the 70 wringer mounted on a washing machine of which only the top is shown; Fig. 2 is an end elevation; Fig. 3 is a side elevation, partly in section, the portion which contains the control mechanism being omitted; Fig. 75 4 is an end elevation, taken in section on the line 4—4 of Fig. 3; Fig. 5 is a sectional end elevation similar to Fig. 4 but with the tension device in its released position, and with the drain board extending to the left instead 80 of to the right; Fig. 6 is a fragmentary perspective view of a portion of the drain board and the latch which cooperates therewith; and Fig. 7 is a fragmentary perspective view 85 illustrating the construction whereby the feed boards are supported.

Referring to the drawings, the wringer is shown as rotatably mounted at the top of a washing machine partly shown at 8. The wringer mechanism, hereinafter described 90 in detail, is supported in a main frame 9 at one end of which within the casing 10 is the mechanism for controlling the starting and stopping of the rollers and the direction in which they are driven by a motor (not 95 shown) which furnishes the power for driving the washing machine and the wringer. The control mechanism within the casing 10, which is actuated by the handle 11, forms no part of the present invention and need 100 not be described in detail. It is also unnecessary to describe the latch mechanism for holding the swinging wringer in any desired angular position with reference to the washing machine, further than to say that 105 it comprises a pivoted latch 13 which co-

operates with a slot in a plate 14 integral with the main wringer frame and with any one of several slots in a plate 15 secured to the top of the washing machine. Said latch 13 is biased to the position shown in Fig. 1, by a spring 16 cooperating with a rod 17 secured to the latch; a knob 18 on the end of the rod 17 being provided so that the latch may be drawn out of engagement with its cooperating slots when it is desired to move the wringer from one angular position to another.

The main supporting frame 9 has integral therewith an upwardly extending end member 19, and a similar end member 20 is rigidly secured to the main supporting frame by screw bolts 21. The shaft 22 of the lower roller 23 is journaled in fixed bearings in said end members 19 and 20. This shaft 22 is power driven through a control mechanism actuated by the handle 11. The shaft 25 of the upper roller 26 is journaled in bearings preferably of the ball type which are movable in recesses in the end members 19 and 20 of the form clearly shown in the drawings. The shaft 25 carries a gear 30 of any well known form which cooperates with a similar gear 31 fixed on the shaft 22; and the roller 26 is thus caused to rotate in unison with but oppositely to the roller 23. Mounted on the tops of the end members 19 and 20 are yokes 33 and 34, which at one end are bifurcated and pivotally connected by pins 35 to lugs 36 integral with the end members 19 and 20. The opposite ends of said yokes are also bifurcated and have pivotally connected thereto by means of a pin 38 a tension device consisting of a bolt 39 having at its free end a winged nut 40 adapted to put under tension a spring 41 which surrounds said bolt and normally cooperates with lugs 42 extending outwardly from the tops of the end members 19 and 20. The said tension devices, therefore, removably cooperate with the end members and serve to hold said yokes yieldingly against the tops of said end members, as shown in Fig. 4. Between the movable bearings 27 and 28 and the yokes 33 and 34 are what may be termed knock-down connections which, in the embodiment shown, consist of cams 44 and 45 rigidly secured to opposite ends of a U-shaped actuating bar 46. Said cams are arranged for movement in either direction within cavities formed in the end members 19 and 20 and within cavities in the bottoms of said yokes 33 and 34; and the ends of said cams which cooperate with the movable bearings 27 and 28 are flat, and the other ends of said cams which cooperate with the yokes 33 and 34 are rounded, all as clearly shown in Figs. 3, 4 and 5. Said cams, when in the position shown in Fig. 4, require the movable bearings 27 and 28 and the yokes 33 and 34 to move in uni-

son; and when said cams are in the position shown in Fig. 5 said movable bearings 27 and 28 are free to move upwardly to a certain extent independently of said yokes 33 and 34.

During the normal operation of the wringer, the cams 44 and 45 stand in the position shown in Figs. 3 and 4. In this condition, the upper roller 26 is yieldingly held in engagement with the lower roller 23. When the wringer is not in use, the bar 46 and the cams 44 and 45 connected thereto should be left in either of their two horizontal positions one of which is shown in Fig. 5. When the cams are in this position, the tension of the springs 41 is not transmitted to the movable bearings 27 and 28. Obviously, it is a simple matter, requiring no adjustment of the tension releasing means, to move the actuating bar 46 and the cams 44 and 45 carried thereby from their vertical position to either of their horizontal positions and vice versa. Any properly instructed operator will therefore have little excuse for not releasing the tension on the upper roller when the wringer is not in use. Moreover, if during use the wringer becomes stalled in an attempt to run too much clothing through it at one time, it is an easy matter for the operator to throw the actuating bar 46 from its vertical to either of its horizontal positions, thereby releasing the tension and allowing the upper roller 26 to move freely away from the lower roller 23. It is also apparent that if the fingers of the operator become pinched between the rollers, the tension on the upper roller may be instantly released by throwing the actuating bar 46 and the cams 44 and 45 in either direction to a horizontal position, which permits the rollers to separate and the operator to withdraw her hand.

Extending from each side of the wringer are feed boards 47 and 48 which are preferably of sheet metal and of the form shown. These feed boards at each side thereof have socket portions 49 best shown, in Fig. 7, which are adapted to cooperate with vertically arranged ribs 50 projecting from said end members 19 and 20 inwardly toward one another. Said feed boards may be easily applied and removed by sliding them in a vertical direction while the socket portions 49 and the ribs 50 cooperate.

Arranged for movement beneath the lower roller 23 is a drain board preferably of sheet metal of the form shown in the drawings. This drain board comprises a main body portion 52 and side portions 53 both of the latter being provided with slots 54 which cooperate with pins 55 projecting inwardly from the end members 19 and 20 of the wringer frame. Lugs 56 projecting inwardly from the end members 19 and 20 are engaged by the top of the side edges of said

drain board when the latter is in either of its two positions which are shown in Figs. 4 and 5. However, in order to positively hold said drain board in either of its operative positions, a latch member 58 of the form best shown in Fig. 6 is provided. This latch member 58 is pivotally secured by a screw 59 to the side of the end member 20, and carries a spring 60 which cooperates with the lug 61 projecting from the end member 20, thereby serving to yieldingly retain said latch member 58 in its operative or inoperative position. Said latch member 58 is of such a form and is so arranged that when the drain board is in the position shown in Fig. 4 the latch member cooperates with a notch 63 in the upper edge of one side of the drain board; as shown in Fig. 6, and when said drain board is in the position shown in Fig. 5 the latch member 58 engages a shoulder 64 in the bottom of one edge of the drain board. The drain board may, therefore, be moved either to the position shown in Fig. 4 or to the position shown in Fig. 5, and in either position is firmly held by the latch member 58.

What is claimed is:

1. In a clothes wringer, the combination of a supporting frame having end members, a roller journaled in said end members, a second roller, bearings for the second roller slidably mounted in said end members, yokes pivotally mounted on the tops of said end members and extending over the bearings for the second roller, tension devices cooperating with said yokes and tending to hold them in a certain position and knock down connections between said yokes and said movable bearings for the second roller which in one position require the movable bearings and yokes to move in unison and

in another position leave said bearings free to move independently of said yokes.

2. In a clothes wringer, the combination of a supporting frame having end members, a roller journaled in said end members, a second roller, bearings for the second roller slidably mounted in said end members, yokes mounted on the tops of said end members and pivotally connected thereto at one end of said yokes, tension devices cooperating with said end members and with the free ends of said yokes and tending to hold the latter in a certain position, and cams between said yokes and said movable bearings for the second roller which in one position require the movable bearings and yokes to move in unison and in another position leave said bearings free to move independently of said yokes.

3. In a clothes wringer, the combination of a supporting frame having end members, a roller journaled in said end members, a second roller, bearings for the second roller slidably mounted in said end members, yokes mounted on the tops of said end members and pivotally connected thereto at one end of said yokes, tension devices pivotally connected to the free ends of said yokes and removably cooperating with said end members whereby said yokes are yieldingly held against the tops of said end members, and cams between said yokes and said movable bearings for the second roller which in one position require the movable bearings and yokes to move in unison and in another position leave said bearings free to move independently of said yokes.

In witness whereof, I hereunto subscribe my name this 10th day of September A. D., 1920.

CHARLES E. REDDIG.
